MEANS FOR CHANGING WAVE LENGTHS.

Application filed May 3, 1915. Serial No. 25,354.

Our invention relates to telegraphy, telephony, or like systems in which the energy employed is in the electro-radiant form for space systems or in the form of high frequency oscillations for conductive systems.

It is an object of our invention to provide, either at the transmitting or receiving station, or both, improved apparatus whereby settings for different wave lengths or frequencies may be made by a single operation of switching mechanism which shall at the same time ensure proper or desired coupling between inductively related oscillation circuits. Further objects of our invention are to provide means for simultaneously switching in or out parts of a loading inductance or parts of a capacity in the closed oscillation circuit, or both. And a still further object is to provide improved structure of an inductance, as a loading inductance, together with means for permitting adjustment of a section while the adjusting means for the other sections are locked.

To these ends we have devised the system and apparatus hereinafter described and constituting an embodiment of our invention.

For an illustration of some of the many forms our invention may take reference is to be had to the accompanying drawings, in which:

Fig. 1 is a diagrammatic view illustrating a typical transmitting apparatus to which our invention may be applied.

Fig. 2 is a diagrammatic view illustrating electrical connection and co-operating switching mechanism for carrying out our invention.

Fig. 3 is a longitudinal section, some parts in elevation, showing one form of apparatus for carrying out our invention.

Fig. 4 is a diagrammatic view, partially structural, illustrating a switching panel controlling the primary of a transmitting apparatus.

Fig. 5 is a plan view of a moving switching element co-operating with the structure illustrated in Fig. 4.

Fig. 6 is a diagrammatic view, partially structural, illustrating switching panel for controlling the secondary and antenna loading inductance.

Fig. 7 is a transverse sectional view, some

parts in elevation, taken on the line X—X of Fig. 3.

Fig. 8 is a diagrammatic view similar to Fig. 2 when used in receiving apparatus.

Fig. 1 shows a typical transmitting apparatus to which reference is made for an explanation of our invention.

Referring to this figure, G is an alternating current generator or other suitable source of current connected in circuit with the primary *p* of a step-up transformer, the primary circuit being controlled by the usual transmitting key *k*. The high tension secondary *s* of the step-up transformer has its terminals connected to either side of the spark gap *g* which may be of the simple type indicated or may be of the quenched gap type, or any other suitable type. The gap *g* is in circuit with the condenser or capacity *K* and the variable portions of the primary *P* of the oscillation transformer, the circuit *PKg* being here shown as a closed oscillation circuit. The open or antenna circuit comprises a variable portion of the secondary *S* of the oscillation transformer, a variable portion of the loading inductance *L*, beyond the inductive influence of the primary *P*, the antenna or aerial conductor *A*, and the earth connection *E*, a radiation meter *M*, such as a hot wire ammeter, being included for purposes of convenience.

When it is desired to transmit energy of a certain frequency or wave length, the variable or sliding contact in the primary circuit is moved to such point on the primary *P*, as for example the point 1, which will ensure the primary circuit producing oscillations of the desired frequency, corresponding with wave length No. 1. This setting may be determined by a wave meter, by calculation, or otherwise. The open or antenna circuit is then attuned to this same frequency or wave length, when the coupling between *P* and *S* is loose, by adjusting the variable contacts on *S* and on *L* until the meter *M* gives a maximum reading. Then by making the coupling between *P* and *S* closer and of such character as is to be employed in transmitting energy having wave length No. 1 the rider or contact sliding on the loading inductance *L* will have to be moved to some new position until the wave meter indicates but a single maximum in the resonance

curve, and the adjustment is further varied until with this single maximum in the resonance curve the meter M indicates a maximum reading for that particular coupling.

- 5 And in this connection the point 1 in the primary P may have to be varied slightly from its first setting. However, by these well-known methods the setting of the inductance L, of secondary S and of primary 10 P are determined for the wave length No. 1. Similarly for another wave length, say No. 2, the settings will be at the points indicated by 2; the settings for a third wave length by 3, and for the 4th wave length by 4.
- 15 In all cases the necessary or desired inductance in the antenna or open circuit for any given wave length can be so proportioned between the secondary S and the loading inductance L that the same mechanical coupling, that is, same physical or mechanical 20 distance or relation between the primary P and secondary S can be obtained for all wave lengths. In making this adjustment of the relative amounts of inductance in S and L 25 for any wave length, if the coupling is too close, the number of turns in S is reduced and the number of turns in L is increased, and conversely if the coupling is too loose, the number of turns in L is reduced, and 30 the number of turns in S is increased.

By our invention we provide switching mechanism, a single movement of which will transfer the movable contacts on P, S and L to the proper points for transmission 35 of these various wave lengths while maintaining the desired or proper coupling between the primary P and the secondary S, this coupling being generally such as will cause a transmission of maximum energy 40 from the closed oscillation circuit to the open antenna circuit.

In Fig. 2 this same general arrangement is shown except that the primary p of the 45 step-up transformer and its circuit are omitted, and there is added the switching mechanism referred to and additional variable inductances or variometers in the open and closed circuits for sake of convenience.

The points 1, 2, 3 and 4 for the four different wave lengths are indicated as in Fig. 1. From the four points 1, 2, 3 and 4 of the primary P connections are made to the four contacts P¹, P², P³ and P⁴ adapted to be engaged by the switch arm P^s. Similarly 55 the four points 1, 2, 3 and 4 on the secondary S are connected respectively with the four switch contacts S¹, S², S³ and S⁴, with which the movable switch arm S^s is adapted to engage. And similarly the four 60 points 1, 2, 3 and 4 on the inductance L are connected with the four switch contacts L¹, L², L³ and L⁴ with which the switch arm L^s is adapted to engage. Inductance L is here shown as divided into two parts, though 65 a greater number may be employed if de-

sired, in order that when one part of the inductance is not in use it may be cut out of circuit (or short circuited as hereinafter described) to prevent energy consumption by such idle portion. For this purpose connections are made from the adjacent ends of the two inductance portions by conductors a and b with the switch contacts c and d which are adapted to be bridged, when both parts of the inductance are to be used, by 70 the switch contact e. The antenna A is connected with the switch arm L^s. And the switch arm S^s connects to the earth E through the radiation meter M and, if desired, an additional variable inductance L^s, 75 which may be set at once for all wave lengths of a group, may be employed.

And in the primary circuit an additional inductance L^p may be employed if required or desired. 80

The switch arms P^s, S^s, L^s and e are mechanically connected together, as by member or shaft f, which may be provided with a hand wheel or other operating device h.

In this figure are shown two condensers or 90 bank of condensers K, K which may be connected in parallel or in series with each other under various circumstances. Switching mechanism for changing these condenser connections comprises stationary switch contacts i, j, m, n, o, and the blank q. The two movable contacts r and t are mechanically connected together but insulated from each other and mechanically connected with the operating mechanism for the switches previously described, this connection causing the contacts r and t to be in position shown, and thereby connect the condensers K, K in parallel with each other, for the three right hand positions of the switch P^s, but 95 when the switch P^s engages with contact P¹, the contacts t, r are shifted toward the left, r remaining in contact with j and engaging the blank q, while t remains in contact with n and connects the same to o, in which case 100 the condensers K, K are in series with each other in the primary circuit, the switch P^s being connected with the contact m. The object of this is to have less capacity in circuit for the shorter wave length or wave 105 lengths so that the corresponding co-operating inductance of the primary circuit will be a substantial part of the primary P. And in reverse movement of the switch arm P^s, the switch contacts t and r are restored to 110 the position shown and occupy such position for all positions of the switch arm P^s when engaging contacts P², P³ and P⁴.

With the parts in the position illustrated in Fig. 2 the connections are such as to 115 transmit wave length No. 3, the amount of inductance L, the coupling between P and S, and the number of turns or length of P in the primary circuit being proper for this 120 wave length. When shifting to any of the 125 wave lengths the connections are such as to 130

other positions the other and corresponding wave lengths will be transmitted while maintaining the coupling at the proper and desired amount and the amount of inductance 5 in the closed and open circuits at the proper amounts.

When the switch arm L^s moves to the left on to contact L^2 or contact L^1 the upper part of the inductance L will not be in use, and it is therefore open circuited for both 10 these positions by the withdrawal of the switch contact e from bridging relation with contacts c and d .

In Fig. 3 the primary P and the secondary S of the oscillation transformer are both shown in the form of spirals carried upon insulating supports 11 and 12 carried by a suitable frame B , the secondary S being movable to and away from the primary P , by 15 sliding in the frame B , for variation of coupling when desired. On the left end of the frame B is the primary circuit control panel and on the right end the panel for controlling the connections to the secondary S as 20 well as the connections to the antenna loading inductance L which latter is shown divided into four parts, L^e , L^d , L^c and L^t , all in the form of flat spirals, supported respectively on the insulating frames or members 25 13, 14, 15, and 16 carried in a frame C .

Secured to the shaft f of Fig. 3 is the member D , of insulating material, the same being shown in plan in Fig. 5, for co-operation with the contacts shown in Fig. 4. The 30 member D carries the fixed contact or switch point P^s adapted to engage the contacts P^1 , P^2 , P^3 and P^4 carried on the frame member B as indicated in Figs. 3 and 4. Beneath the contacts P^1 , P^2 , and P^3 are the arc 35 shaped contacts u , v , and w , the latter being connected also to the short arc shaped contact x associated with switch contact P^1 . The member D has three rows of holes, the holes of each row being on a radial line, 40 these holes adapted to receive the plug contacts p^1 , p^2 and p^3 carried by the removable insulating plate or member F , the plug p^1 being in permanent electrical connection with the switch point P^s in all positions and the plugs p^2 and p^3 being electrically connected 45 with each other. It will be understood that the member F carrying the aforementioned plugs may be inserted in the member D in the position shown in Fig. 5 or in either of the positions to the right or left thereof. In all positions the plugs extend 50 through the holes of the member D , p^1 co-operating with the arc shaped contacts u and x , the plug p^2 with the arc v , and the plug 55 p^3 with the arc w . With the plugs in the position indicated in Fig. 5, and with the switch contact P^s in engagement with P^2 , P^3 or P^4 the condensers K , K will be found to be connected in parallel with each other. 60 With the parts in the same position and the

switch point P^s in engagement with contact P^1 the condensers K , K will be in series with each other. With the plugs carried by member F disposed to the right of the position illustrated in Fig. 5, that is, in the right hand row of holes, the following condenser connections will result: with P^s on P^1 or P^2 the condensers K , K will be in series with each other in the oscillation or closed circuit. With P^s on P^3 or P^4 the condensers 75 will be in parallel with each other and in series in the oscillation or closed circuit. With the plugs carried by member F moved to the left hand row of holes in member D the condensers K , K , will be connected in 80 parallel with each other when P^s is on P^1 , P^2 , P^3 or P^4 . And with the switch point P^s on contact P^1 , whatever the nature of connection of condensers K , K , either series or parallel, a condenser K^1 , for use on very short 85 wave lengths, may be thrown into series with them by opening the switch y which when closed short circuits the condenser K^1 ; the switch y may be manually operated through shaft f by suitable mechanical connection 90 therewith.

The switching mechanism above described and involving the members F and D permits a standard apparatus involving them to be used under various conditions or characteristics of primary circuits as regards primary circuit capacity and inductance of the leads or connections. With a given installation it might be necessary or advantageous to have the condensers in series for certain 100 of the wave lengths, as No. 1 and No. 2, and in parallel with each other for other wave lengths, as No. 3 and No. 4, while with another installation it might be necessary or advisable to have the condensers in parallel 105 for all four wave lengths.

At the other end of the frame B , Fig. 3, is the panel arrangement shown in Fig. 6. Here the switches S^s and L^s of Fig. 2 are in effect a single conducting member rotated by but insulated from the shaft f . There is a permanent connection z from the switch contact L^1 to the rotating arm L^s , S^s whereby those parts of the inductance L which are not co-operating for each setting are short circuited. Thus when L^s is on contact L^2 the section L^e of the loading inductance is short circuited. When on L^3 , as shown, sections L^e and L^d are short circuited. And when on L^4 , sections L^e , L^d and L^c are short circuited. This short circuiting arrangement is the alternative of the open circuit arrangement by switch e of 115 Fig. 2.

It will be noted from Figs. 2 and 6 that the connections to the inductance L are shown as variable in their position. With any given antenna or complete outfit it is found that from time to time there is a 120 variation or change in the electro-magnetic 125

or electrostatic constants of the apparatus necessitating, if sharpest tuning or maximum effects are desired, a slight adjustment of these connections with the loading inductance. To this end the apparatus in the lower part of Fig. 3 and in Fig. 7 is employed. With each of the inductance sections L^c , L^d , L^e and L^f co-operates a sliding contact c^1 , engaging L at 1, 2, 3 and 4, which
 10 embraces the edge of the inductance conductor and is rotated by and movable radially on the arm a^1 to adjust with nicety the amount of inductance L in the open circuit. These contacts c^1 are not moved
 15 simultaneously. Each is movable only when the switching apparatus is set for the particular wave length for which said contact c^1 comes into operation and is effective in slightly varying the amount of inductance L which is in use for the wave length
 20 in question. For this purpose the arms a^1 are loosely pivoted upon the shaft f^1 and each of the arms a^1 carries teeth or projections a^2 adapted to engage in corresponding
 25 depressions in the bushings a^3 which rotate with the shaft f^1 but may move longitudinally with respect to the shaft f^1 in opposition to the springs a^4 , one end of each being connected to its bushing a^3 and its other
 30 end to a pin a^5 carried by the shaft f^1 . Back of each member a^3 is a wedge-shaped member b^1 having its point disposed between the member a^3 and a collar b^2 secured upon the shaft f^1 . Each member b^1 is at the
 35 lower end of a rod b^3 whose upper end engages a cam. These cams are indicated at c^2 , c^3 , c^4 and c^5 and are all rigidly secured upon the shaft f^2 connected in definite mechanical relation with the shaft f , as by
 40 sprocket chain c^6 passing over sprocket wheels on the shafts f and f^2 .
 When the operator moves the handle h for setting the switches P^s , L^s , and S^s he will move it, for example, to such position
 45 that switch contacts P^2 , L^2 and S^2 are brought into circuit. In so rotating the shaft f , the shaft f^2 will be rotated to such position that the cam c^3 will depress the rod b^3 to cause the wedge b^1 to force the clutch
 50 member a^3 into engagement with the arm a^1 carrying the contact c^1 which co-operates with the inductance section L^d . The result is that by turning the hand wheel h^1 secured to shaft f^1 only that arm a^1 co-operating with inductance L^d may be rotated to adjust with nicety the position of the contact c^1 of that inductance section; all the other arms a^1 are incapable of movement at this time. And so for each wave length
 55 transmitted, or for each position of the shaft f , one or another of the cams operates its co-acting rod b^3 to make possible fine adjustment of one of the inductance sections, and it is always that one which is effective
 60 for the particular wave length transmitted.

The inductance sections L^c , L^d , etc. are preferably within inductive influence upon each other, in which case a relatively smaller adjustment of contact c^1 upon its associated section is necessary to effect a given variation of inductance than in the case where those sections are beyond inductive influence by each other. 70

While the apparatus thus far described has been transmitting apparatus it will be 75 understood that the same functions may be procured for receiving apparatus.

Thus in Fig. 8 Fig. 2 has been reproduced but in place of the apparatus shown in the primary circuit of Fig. 2 receiving apparatus is shown. And what was the primary P of Fig. 2 is now in reality the secondary of an oscillation transformer which is included in circuit with the variable capacity K^2 a variable inductance or variometer V 85 and a wave responsive device or detector W in shunt with which is connected a telephone receiver T or other suitable instrumentality. 80

Here again it will be understood that for 90 receiving on different wave lengths the operator need merely turn the hand wheel h to any of the positions, and then by varying V and K^2 maximum response will be obtained by tuning. 95

While with our apparatus hereinbefore described the change from one wave length or frequency to another is accomplished by a single movement, as by a single actuation of the hand wheel h for a given position of the secondary S with respect to the primary P , or a given separation between them, our invention comprehends also the accomplishment of the same result for different relative positions of or separations between the secondary S and the primary P , both when such separation is changed by manually shifting one or the other and when such separation is changed or varied by mechanical means. 100

The shaft f need not be rotated or actuated manually but may be actuated by a suitable motive device electrically or otherwise controlled from a distance to cause the shaft f to partake of the proper degrees of rotation 115 for shifting the mechanism to the proper positions for the various wave lengths or frequencies. 110

While we have herein shown and described the inductance L in the open or antenna circuit as divided into sections L^c , L^d , etc., with means for adjusting any one of these sections while the others are locked against such adjustment, it is to be understood that we may use in the other or associated circuit, as 120 the primary circuit, an inductance which may be similarly varied, and while any one section is variable, the others are locked against variation. In other words the inductance L^b of Fig. 2 could be so arranged 125 130

in sections each variable or adjustable while the others are locked against variation or adjustment, the mechanism for this purpose being like that in the lower half of Fig. 3 and coupled to the shaft *f*.

What we claim is:

1. The combination with an antenna, of primary and secondary windings of an oscillation transformer, switches and connections therefrom to said primary and secondary windings for maintaining predetermined couplings between them for each of a plurality of different oscillation frequencies, a plurality of capacities in circuit with one of said windings, and switches for altering the relations of said capacities to the circuit including them, and means common to all of said switches for actuating them in unison.
2. The combination with an antenna, of primary and secondary windings of an oscillation transformer, an inductance in circuit with one of them, switches and connections with said primary, secondary and said inductance for maintaining predetermined couplings between said primary and secondary windings, and procuring the requisite amount of inductance for each of a plurality of oscillation frequencies, said inductance being divided into sections, a switch for preventing dissipation of energy in a section of said inductance which is not co-operating with said primary and secondary windings, and means common to all of said switches for actuating them in unison.
3. The combination with an antenna, of primary and secondary windings of an oscillation transformer, an inductance in circuit with one of them, switches and connections with said primary, secondary and said inductance for maintaining predetermined couplings between said primary and secondary windings, and procuring the requisite amount of inductance for each of a plurality of oscillation frequencies, said inductance being divided into sections, a switch for preventing dissipation of energy in a section of said inductance which is not co-operating with said primary and secondary windings, a plurality of capacities in circuit with one of said windings, and a switch for altering the relations of said capacities with respect to the circuit in which they are included, and means common to all of said switches for actuating them in unison.
4. The combination with an antenna, of a primary and secondary of an oscillation transformer, additional inductance switches and connections with said primary, secondary and said inductance for maintaining a predetermined coupling between said primary and secondary and procuring the requisite amount of inductance for each of a plurality of oscillation frequencies, means for independently varying the connections to said inductance, but normally in unlocked

relation therewith, and means for locking said last mentioned means to said connections.

5. The combination with an antenna, of a winding of an oscillation transformer, an inductance in circuit therewith, switches for changing the amount of said inductance and said transformer winding in circuit, means causing all of said switches to move in unison and means for preventing dissipation of energy in that part of said inductance which is not included in circuit.

6. The combination with an antenna, of a winding of an oscillation transformer, a separate inductance in circuit therewith, a switch connecting said winding and said inductance and serving to simultaneously alter the amount of each in circuit, and means for simultaneously short circuiting that part of the inductance not in circuit with said transformer winding.

7. The combination with antenna, of an inductive winding, capacities associated therewith, a movable switch element for bringing into circuit more or less of said winding, stationary contacts connected with said capacities, movable contacts adapted to co-operate with said stationary contacts, and means mechanically connected with said movable contacts for changing the relation of said capacities in circuit after predetermined variation of said winding.

8. The combination with an antenna, of a plurality of inductance sections, a variable connection to each section for varying the amount of such section to compensate for antenna variations, switching mechanism connecting to said variable connections for determining the number of sections in circuit, means controlling the variable connections but normally disconnected therefrom, and means controlled by the switching mechanism for operatively connecting said last mentioned means to said variable connections.

9. A radio system comprising the combination with an oscillation circuit, of a plurality of inductance sections, a variable connection to each section for varying the amount of such section to compensate for circuit variations, switching mechanism connecting to said variable connections for determining the number of sections in circuit, means for independently varying the connections to said inductance, but normally in unlocked relation therewith, and means for locking said last mentioned means to said connections.

10. A radio system comprising the combination with an oscillation circuit, of a plurality of inductance sections, a variable connection to each section for varying the amount of such section in circuit to compensate for circuit variations, switching mechanism for throwing in circuit said con-

- 5
- nections in succession for determining the number of sections in circuit, means controlling the position of the variable connections but normally out of operative relation therewith, and means controlled by said switching mechanism for placing said last mentioned means in operative relation with the connection which is then in circuit.
11. The combination with an antenna, of
- 10 a primary and secondary of an oscillation transformer and their circuits, additional inductance in one of said circuits, switching mechanism including switches and connections with said primary, secondary and said
- 15 inductance for maintaining a predetermined coupling between said primary and secondary for each of a plurality of oscillation frequencies, variable contact elements for said inductance connections, means for independently varying said contact elements, and normally in unlocked relation therewith, and means controlled by said switching mechanism for locking to said last mentioned means a portion of said contact elements.
12. A radio system comprising an antenna, inductance and capacity, movable means common to said inductance and capacity for throwing in circuit a predetermined amount of each, and switching mechanism carried by said means for varying the relation between said inductance and said capacity.
13. A radio system comprising a tuning circuit, inductance therein having a plurality of sections, condensers, and switching mechanism connecting to said sections for determining the number of sections in circuit and for simultaneously changing said condensers from parallel to series relation in said circuit, and vice versa.
14. A radio system comprising a tuning circuit, inductance therein having a plurality of sections, capacity, a movable switch element connecting to said sections and said capacity for determining by its movement the amount of each in circuit, and means carried by said switch element for varying the amount of capacity without movement of said movable switch element.
15. The combination with the primary and secondary windings of an oscillation transformer and their current paths, of additional inductance in one of said current paths and capacity in the other of said current paths, separate means for each of said inductance, said primary winding, and said secondary winding, for determining the amount of each in circuit, means actuating all of said means in unison, and means co-operating with said last mentioned means for changing said capacity after predetermined variation of the winding in circuit therewith.
16. The combination with variable primary and secondary windings of an oscillation transformer and their current paths, of variable capacity in one of said paths, a variable tuning element in the other of said paths, a switch for each of said windings and for said tuning element for determining the amount of each in circuit, means for actuating said switches in unison, and means controlled by said last mentioned means for changing the amount of effective capacity after a predetermined variation of the transformer winding in circuit therewith.
- In testimony whereof we have hereunto affixed our signatures.
